UNITED STATES PATENT OFFICE.

CARL STOETER, OF NEW YORK, N. Y., ASSIGNOR TO NEW YORK BUTTON WORKS, OF NEW YORK, N. Y., A CORPORATION OF NEW YORK.

DESIGN FOR A BUTTON.

No. 40,135.

Specification for Design.

Patented July 13, 1909.

Application filed May 14, 1909. Serial No. 496,083. Term of patent 3½ years.

To all whom it may concern:

Be it known that I, CARL STOETER, a citizen of the United States, residing at 264 Canal street, borough of Manhattan, in the city, county and State of New York, have invented a new, original, and ornamental Design for Buttons, of which the following is a specification, reference being had to the accompanying drawings, forming part thereof.

Figure 1 is a plan view and Fig. 2 an edge view of a button showing my new design.

I claim:

The ornamental design for a button substantially as shown in the drawing.
